Primary Examiner — Kelley Donnelly(74) *Attorney, Agent, or Firm* — Sheridan Ross P.C.**CLAIM**

The ornamental design for a storage device, as shown and described.

DESCRIPTION

FIG. 1 is a top perspective view of the storage device;

FIG. 2 is a bottom perspective view thereof;

FIG. 3 is a top plan view thereof;

FIG. 4 is a front elevation view thereof;

FIG. 5 is a right elevation view thereof;

FIG. 6 is a bottom plan view thereof;

FIG. 7 is a left elevation view thereof; and,

FIG. 8 is a rear elevation view thereof.
